UNITED STATES PATENT OFFICE.

JAMES V. WASHBURNE, OF SYRACUSE, NEW YORK.

COMBINED TAG AND FASTENING-CLIP.

1,274,222.

Specification of Letters Patent.

Patented July 30, 1918.

Application filed November 7, 1913. Serial No. 799,668.

To all whom it may concern:

Be it known that I, JAMES V. WASHBURNE, a citizen of the United States, residing at Syracuse, in the county of Onondaga and State of New York, have invented an Improvement in Combined Tags and Fastening-Clips, of which the following is a specification.

My invention relates to tags adapted to be attached to fabrics and other goods for the purpose of denoting quality, size, style, price, etc., and consists of a card or tag of any desired size or shape and of suitable material, to which is permanently secured a fastening clip by means of which the card may be attached to the goods in such manner that a smooth surface is presented on all sides, whereby the danger of injury to a person's fingers or hands by contact with a sharp prong or tooth in handling the goods is prevented.

The details of the invention are herein-after particularly described.

In the accompanying drawing:—

Figure 1 is a plan view of the clip detached from the tag and showing it in the form after being stamped out of a sheet of metal.

Fig. 2 is a plan view of the tag detached from the clip.

Fig. 3 is an edge view of the clip shown in Fig. 1.

Fig. 4 is a similar view showing the eyelet and tooth formed on the same side of the clip.

Fig. 5 is an edge view showing the combined tag and clip attached to a piece of goods.

Fig. 6 is a plan view of the same.

Fig. 7 is an edge view of the combined tag and clip with the jaws of the clip open ready for attachment to the goods.

Fig. 8 is a plan view of the clip detached showing a modification in shape, and

Fig. 9 is a sectional side view showing the device attached to a thin character of goods.

All the figures of the drawing are in enlarged size for clearness.

Similar reference numerals indicate like parts throughout the several views.

1 indicates the clip which is provided with an eyelet 2 adjacent one end and a prong or tooth 3 adjacent its other end, which are preferably stamped up of an integral piece.

55 The clip is formed of flattened or sheet metal

and its ends are preferably rounded to avoid presenting sharp corners.

4 represents the card or tag provided with a hole 5 of a size adapted to receive the eyelet 2 on the clip 1.

After the eyelet 2 has been inserted through the hole 5 in the tag 4, its edge is flanged down over the surface of the tag and the clip is thereby permanently secured to the tag.

At the center of its length, the clip 1 is bent over toward itself so that its two opposing parts or wings are in oblique relationship to each other in readiness for applying the tag and fastener to the goods 6, as illustrated in Fig. 7. The eye 2 is external and projects upwardly or away from the space between the wings and the prong or tooth 3 projects into said space.

To facilitate the bending of the clip, the central part may be cut out as shown in Fig. 1, or its opposite sides may be notched or cut away as shown in Fig. 8.

This not only assures the bend being formed at the proper place in the clip, but also lessens its weight.

The goods 6 to which the tag is to be attached are placed between the jaws of the clip and the free end of the clip is then pressed against the goods forcing the tooth 3 through the same and into the eyelet 2, which forms a receptacle for the point of the tooth, protecting it on all sides from contact with another object, thereby preventing the tooth being bent out of position.

The tooth 3 is preferably of a length so that when the tag is attached to the goods, the point of the tooth does not project sufficiently near to the outer edge of the eyelet to come into contact with the finger of a person in attaching the tag or in handling the goods after the tag has been attached, and the clips are made of various sizes to be adapted for attachment to different thicknesses of material. In cases where the material to which the tag is attached is extremely thin, it is not necessary to press the jaws of the clip tightly upon the material, but if they are so

pressed that the point of the tooth should project slightly beyond the opening in the eyelet, a very slight blow with a light hammer will upset or turn the extreme point of the tooth back into the eyelet, which will also serve to lock the jaws of the clip with the material between them, while a smooth

surface is presented at the opening in the eyelet. This is illustrated in Fig. 9.

In shipping my combined tag and fastening clip in large quantities, the clips may be left in the flattened form shown in Figs. 1, 3, 4 and 8, as the cut out in the center, or the notches or cut away assures the easy bending on the proper line of the clip when it is desired to attach a tag to the goods.

10 It will be readily seen that a simple pressure produced by the fingers will bring the clip from the open position shown in Fig. 7, to the closed position shown in Figs. 5, 6 and 9, whereby the tooth on the free jaw of the clip will penetrate the fabric between the jaws, and its point will pass into the eyelet on the attached jaw in which it is protected from contact with any other object.

15 My invention combines in one device both a tag and a clip or fastener whereby the tag can be easily and quickly applied to an article of fabric which it is desired to number

or mark, and which can be easily removed therefrom without injury to the goods.

I claim as my invention:

The combination of a clip folded upon itself to form opposing portions or wings, one of said portions being formed with an external outwardly projecting tubular eye and the other being formed with an angular 30 prong for entering the eye, the prong being located in the space between the wings and the eye outside of such space, and a tag mounted on the eye, the eye being of greater diameter than the prong and adapted to retain the tag, substantially as and for the purpose described.

25 Signed by me this 3rd day of November 1913.

JAMES V. WASHBURN.

In the presence of —

R. M. HEUSE,
B. B. AYLESWORTH.
